FIG. 2.

FIG. 3.

Inventor:
Arthur Falk.

By *H. Jacob Dugler*
Attorney.

UNITED STATES PATENT OFFICE.

ARTHUR FALK, OF NEW YORK, N. Y., ASSIGNOR TO FALK TOBACCO CO., OF NEW YORK,
N. Y., A CORPORATION OF NEW YORK.

DISPENSING RECEPTACLE OR PACKAGE.

1,253,222.

Specification of Letters Patent. Patented Jan. 15, 1918.

Application filed March 11, 1916. Serial No. 83,502.

To all whom it may concern:

Be it known that I, ARTHUR FALK, a citizen of the United States, residing at New York, in the county of New York and 5 State of New York, have invented certain new and useful Improvements in Dispensing Receptacles or Packages, of which the following is a specification.

This invention relates to the subject of 10 packages, such, for example, as those used in connection with cigarettes, and the primary aim of the invention is to provide simple and efficient means whereby the contents of the package, in pre-determined 15 quantities, may be projected from the package to facilitate removal of such contents without damage to the package or the goods that are contained therein.

A simple and practical embodiment of the 20 invention is shown in the accompanying drawings, wherein—

Figure 1 is a perspective view of a package equipped with my invention.

Fig. 2 is a vertical sectional view.

25 Fig. 3 is a detail plan view.

The invention is of particular utility in connection with cigarette packages of the well known flexible type usually including an outer wrapper or label, an intermediate 30 weather-proof protector of foil, and a lining of paraffined sheet material, the package as illustrated being designated generally by the numeral 1, and the lining thereto by the numeral 2.

35 The invention is designed to project the contents, or a part of the contents of the package beyond the mouth of the package so that they may be removed by the user, said invention consisting of a pull strip 3,

40 preferably of flexible material, that extends into and across the inner surface of the bottom of the package and has one end portion pasted or otherwise attached to the inner surface of the side of the lining 2 above the bottom of the package. The other or free end of the pull strip 3 projects through and slightly beyond the mouth of the package and forms a finger grip 4.

An ejector plate 5, formed of suitable 50 material that is comparatively stiff, is provided with a pair of spaced parallel slots 6 through which the strip 3 is threaded, the said plate 5 being disposed beneath the lower end of the contents of the package 1.

55 As shown in Fig. 2 of the accompanying

drawings, the ejector 5 normally lies flat on the bottom of the package 1, and when it is desired to project some of the cigarettes beyond the mouth of the package, the mouth of the package is opened and the 60 finger-grip 4 extended into position to be grasped by the user. An outward pull on the finger grip 4 will then project some of the cigarettes, as shown in Fig. 1 of the accompanying drawing so that they can be 65 readily removed from the package.

The ejector 5 may be of any size relative to the size of the package. As shown in Fig. 2, it may be of a size to cause two 70 rows of cigarettes to be projected, and as shown in Fig. 3, the corners of the plate may be rounded so that no damage will be done to the lining 2 incidental to the movements of the plate.

The plate 5 is formed of comparatively 75 stiff material and the slots 6 formed therein are large enough to permit the strip 3 to freely slide therethrough so that the lifting movement of the strip causes said strip to slide relatively to the said plate. Such 80 movement of the strip 3 relative to the plate 5 prevents the said plate being pulled to an inoperative position relative to the contents of the package.

I claim as my invention:

1. An ejecting device for the contents of receptacles comprising a flexible pull strip having one end fastened to a receptacle, the strip extending beneath the contents of the receptacle, and an ejector carried by the pull 90 strip and comprising a flat plate disposed beneath the contents of the receptacle and having its body portion provided with spaced parallel slots through which the free portion of the pull strip is threaded to permit the plate to automatically adjust itself 95 relative to the contents of the receptacle.

2. In a device of the character described, the combination with a receptacle, of a pull strip therein and extending beneath the contents of said receptacle, and an ejector plate within the receptacle and disposed beneath the contents of the receptacle, the ejector plate being freely slidable on the pull strip to permit the plate to adjust itself relative 100 to the contents of the receptacle, the edge portions of the ejector plate being shaped to prevent movement of the plate damaging the receptacle.

3. An ejecting device for the contents 110

of receptacles comprising a flexible pull strip having one end so connected to a receptacle as to prevent inward motion, the strip extending beneath the contents of the 5 receptacle, and an ejector carried by the pull strip and comprising a flat plate disposed beneath the contents of the receptacle and having its body portion provided with spaced apertures through which the 10 free portion of the pull strip is threaded to

permit the plate to automatically adjust itself relative to the contents of the receptacle.

In testimony whereof I have affixed my signature in the presence of two witnesses. 15

ARTHUR FALK.

Witnesses:
